UNITED STATES PATENT OFFICE.

LAURITZ HAASTED, OF DRAMMEN, NORWAY.

STOP BLOCK AND SWITCH FOR RAILWAY TRACKS.

Application filed November 30, 1923. Serial No. 677,767.

To all whom it may concern:

Be it known that I, LAURITZ HAASTED, a subject of the King of Norway, residing at Drammen, Norway, have invented certain new and useful Improvements in Stop Blocks and Switches for Railway Tracks; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 My invention relates to hand operated turnover stop blocks for railway tracks. In such stop blocks it is known to arrange the control locks of the stop block and of the switch, respectively, in such manner that 20 they are mutually dependent of each other, the arrangement being such that the key of the control lock of the stop block, which has normally its place in the control lock of the switch, can only be released from this lock 25 by aid of a key fitting into a key hole in this control lock, and the turning of which releases the key of the stop-block control lock.

In this arrangement the stop block is, 30 however, free to be turned back into blocking position, while the switch is still turned on to the branch track.

The object of my invention is to provide an arrangement in which the turning back 35 of the thrown off stop block into its blocking position is prevented so long as the switch blades are open to the branch track or are open to the main track, but are un-locked.

40 In the accompanying drawings Fig. 1 is a plan diagram of an arrangement according to my invention. Fig. 2 is a plan view of the stop block locking arrangement, and Fig. 3 is a corresponding side view of the 45 same. Fig. 4 is a plan view of a modified locking arrangement. Fig. 5 is a diagrammatic side view of a control lock of a type suitable for the switch and Fig. 6 is a plan view on a larger scale of a control lock of 50 a type suitable for the stop block. Fig. 7 is a diagrammatic view of an electric switch for operating a control circuit.

55 The turn-over stop block *a*, whose pivot bolt *e* is turnably mounted in journals *d*, *d* in well known manner, is provided with locking levers or plates *m* and *q*, placed,

respectively, in front of and behind the upright portion of the stop block.

A control lock *b* is fastened to the journal *d* or any other suitable part adjacent to the locking levers *m* and *q*. This lock which may be of any known construction suitable for the purpose is provided with two lock bolts *i* and *j*, each controlled by a separate key *k* and *l*, respectively. These 60 two keys are in well known manner arranged so as to be mutually dependent of each other.

The lock *b* is arranged in such manner that the key *k* actuating the lock bolt *i* 70 can be removed from the lock only when the stop block *a* is in its blocking position, lying across the rail, and with the lock bolt *i* in engagement with the locking lever *m*, thereby preventing the throwing off of the stop 75 block *a*.

The lock bolt *j* at the same time is in its retracted position. The key *l*, needed for actuating said lock bolt *j*, which is also the only key by aid of which the control lock *c* of 80 the switch (Fig. 1) may be actuated, is hereby locked in place in the stop block control lock *b*. In this position the locking lever or plate *m* or eventually the mutual dependence between the two lock bolts, will prevent the retracting of the lock bolt *j*, and the key *l* therefore will be locked in its position in the lock as long as the stop block remains in this position; at the same time, however, the lock bolt *i* may be retracted 85 by turning the key *k*, which is thereby released from the lock.

When the switch is locked with its blades open to the main track *O* (Fig. 1) and the stop block *a* is locked in its active position, 90 the switch is to be shifted into position for the branch track *N*, the key *l*, which is normally to be kept in the station master's office, is taken out to the stop block *a* and inserted into its key hole *l'* (Fig. 2) and is 95 turned about. Hereby the lock bolt *i*, which has hitherto been locking the stop block *a* in its operative position, is retracted, and the stop block now may be swung into its inoperative position. 100

In this latter position of the stop block the key *l*—(either owing to the removal of the lever or plate *m* from the path of its lock bolt or in consequence of reciprocally guided motions of the two lock bolts mentioned above)—will be free to be turned, 110 thereby pushing the lock bolt *j* into engage-

ment with a corresponding groove in the lever or plate q , thereby locking the stop block in its inoperative (downturned) position.

5 Only when this result has been obtained the key l is free to be removed from the stop block lock in order to be used for unlocking the control lock c of the switch and prior to laying the switch blades over to the branch track N . In this inactive position of the stop block the lever or plate q is lying across the path of the lock bolt i , thereby locking the key l into its keyhole.

10 The stop block being thus turned down and locked into its inoperative position, the branch track N is now open and switched in.

15 When the points are again switched back to the main track and the control lock c of the switch is locked, the key l is free to be removed from it and is inserted in its keyhole l' in the stop block control lock b , and turned round, thereby retracting the lock bolt j , and simultaneously locking itself in the keyhole. The stop block is now free to be turned over into its operative or blocking position across the rail, whereupon the key l is turned, thereby pushing the lock bolt i into engagement with the lever or plate, and locking the stop block in position, whereupon this key is free to be taken out of the lock r and removed to the station master's office, where it is kept in a place destined for it, or preferably, is inserted in a special electric switch hereinafter described, thereby cutting in a control circuit to the nearest station on both sides, and signalling thereby a free main line.

20 40 Through the arrangement described in the foregoing it is made impossible to throw the stop block in operative position so long as there is any possibility of the switch control lock allowing the points to be switched on to the branch track.

45 Instead of a single control lock with two bolts and two keys dependent of each other, I may of course use two independent control locks, the dependency of the two keys being then obtained by letting the levers or plates m , q in one position act as stops for the lock bolts, thereby preventing the turning of the corresponding key (as illustrated in Fig. 3).

50 55 In Fig. 4 is illustrated a modified lock arrangement, which differs from that described in the foregoing only therein that the two control locks b , r of the stop blocks are placed independent of each other on opposite sides of the stop block, which latter is in this case provided with two sets of locking levers or plates m , q , each corresponding to one control lock. It will, however, be understood, that the arrangement of the control lock or locks and of

the corresponding locking parts in the stop block may be varied in a great number of ways without exceeding the scope of the invention.

60 The mechanical arrangement of the central locks is diagrammatically illustrated in Figs. 5 and 6.

65 Fig. 5 illustrates the control lock c of the switch in its locked position, i. e. with the key removed. The locking bar t of the switch which is passed through a boring in the rail web, is then locked in the position shown in full lines in Fig. 5, thereby locking the moveable tongue or blade u of the switch in its open position. When the 70 switch is to be shifted, this is effected by inserting the key l , in the lock c , and turning it about so as to allow the bar t to be drawn out in the position shown in broken lines to the left on Fig. 5. This being done, 75 the tongue or blade u is free to be shifted to the position shown in broken lines adjacent to the stock rail, but as long as the bar t is in this position the key l cannot be removed from the key hole o , this being only 80 possible when the bar t has been pushed into its tongue locking position.

85 Fig. 6 is a diagram of the control lock r on Fig. 3 or 4. When the key l is inserted in the key hole l' , the lock bolt i locking the 90 stop block in its operative position is retracted, the key l being thereby locked in the lock, it being only possible to remove it when the lock bolt i is in its pushed out position.

95 100 After having swung off the stop block a , the key l of the other control lock is turned round, pushing out the lock bolt j thereby locking the stop block in its inoperative position. Now the locked key l may be removed from its lock b , and then inserted in the switch control lock, thereby allowing the shifting of the switch bar t .

105 110 As stated above the key l when removed from the lock r may be used for operating an electrical switch such as illustrated in Fig. 7. Said key being inserted in the switch displaces a lever 1 against the pull of a spring 2. The lever has an insulated portion 3 which, on the key l being fully 115 inserted, is turned so as to bring two spring contacts 4 and 5 together, thereby closing the signalling circuit 6, 7 to the nearest stations.

115 120 As already mentioned my invention does not comprise the specific mechanical construction of the control locks, any suitable type of control locks being adaptable for the novel control arrangement forming the object of this invention.

125 Claims—

120 130 1. In hand operated turnover stop blocks for railway tracks with a control lock for the switch and a control lock for the stop block, the combination of the stop block

control lock, and the switch control lock, with means for making said locks dependent on each other in such a way as to prevent the shifting of the stop block from its inoperative to its operative position until the key of the switch control lock has been placed into position in the control lock of the stop block. 25

2. The combination of a stop block for a switch rail, a control lock for the latter, a lock for the stop block, means for actuating the last named lock to permit the stop block to be moved into inoperative position, and a key for actuating the switch control lock normally retained in the lock of the stop block when the latter is in operative position. 30

3. The combination of a stop block for a switch rail, a control lock for the latter, a lock for stop block to prevent the shifting of the block into inoperative position, a key to actuate the lock of the stop block whereby

the latter may be moved into inoperative position and release the key of the switch control lock. 35

4. The combination with a switch rail, of a control lock for the latter, a stop block movable relatively to the rail, means to lock the block in operative position, means to lock the block in inoperative position, said locking means including keys one of which is adapted to actuate the locking means to permit the stop block to be moved into inoperative position and the other key adapted to lock the block in inoperative position and to actuate the rail control lock. 40

In testimony that I claim the foregoing as my invention, I have signed my name in presence of two subscribing witnesses.

L. HAasted.
